CIRCULATOR FOR BOILER FURNACES AND THE LIKE

Application filed April 16, 1929. Serial No. 355,590.

This invention relates to circulators for boiler furnaces and the like, and more particularly to a device for promoting the circulation of air about the furnace.

- 5 An important object of the invention is the provision of means utilizing the heat generated by the boiler furnace to speed up the circulation of air to a point beyond that provided by thermal action alone.
- 10 A further and more specific object of the invention is to provide in combination with a boiler furnace having a water chamber in which water is heated to generate steam a fan for causing circulation of air about
- 15 the exterior of the boiler furnace and a turbine operated by steam generated in said chamber for operating the fan.

A still further object of the invention is the provision of a structure of this character which may be included in the space provided between such boiler furnace and the jacket with which such device is usually provided.

These and other objects we attain by the construction shown in the accompanying drawings, wherein for the purpose of illustration is shown a preferred embodiment of our invention and wherein:—

Figure 1 is a side elevation partially in section of a furnace embodying a circulator constructed in accordance with our invention;

Figure 2 is a plan view of the furnace with the top wall removed;

Figure 3 is a fragmentary side elevation of the blower fan.

Referring now more particularly to the drawings, the numeral 10 generally designates a furnace having a boiler chamber 11 provided with an outlet 12 opening through the upper end wall of the furnace and likewise provided in such upper wall with a filling opening or neck 13 having a removable cap 14. In accordance with our invention, we surmount the outlet 12 with a turbine casing 15 having disposed therein a turbine wheel 16, the shaft 17 of which is vertically directed and has secured to its upper end radially extending arms 18. The upper end of the furnace is surrounded by a blower

fan structure 19 including angularly disposed vanes 20 for causing an upward blast of air. To this blower structure, the ends of the arms 18 are secured. The exhaust pipe 21 of the turbine casing is extended 55 downwardly along the wall of the furnace and into a water pan 22, which contains water to a level above the upper end of the exhaust pipe.

The furnace is surrounded by a suitable ornamental casing 23, the upper wall 24 of which is removable to permit ready access to the fan or turbine and is perforated to permit the ready flow of air therethrough, as in the usual structure of this character.

In operation of the device, when the heat of the furnace generates steam within the chamber 11, this steam passing through the outlet 12 will operate the turbine, causing the blower fan 19 to rotate and promote circulation of air upwardly through the casing. The exhaust of the fan passes through the outlet pipe 21 into the water pan 22, which acts both as a silencer and as a condenser for the steam.

A structure of this character provides for rapid circulation of air about the furnace, thereby promoting the heating efficiency thereof. At the same time, the small amount of moisture ordinarily given off by the water chamber is augmented by a slight steam escape which supplies the necessary humidity.

It will be obvious that this structure is capable of a certain range of change and modification necessary to its application to various types of boiler furnaces without in any manner departing from the spirit of the invention, and we accordingly do not limit ourselves thereto except as hereinafter claimed.

We claim:—

1. In combination with a furnace having a water chamber heated during operation of the furnace, a casing surrounding the furnace, a blower surrounding the furnace adjacent the upper end thereof and within the casing and adapted when rotated to cause an upward circulation of air within the casing, a turbine supported from the furnace and connected with the water chamber to receive

steam therefrom, a driving connection between the turbine and said blower, there being a water pan within the casing and adjacent the lower end thereof, and means for directing the exhaust from the turbine into the water in said pan.

2. In combination with a furnace having a water chamber heated during operation of the furnace, an outlet for said chamber projecting through the top of the furnace, a turbine casing having a vertically directed rotor shaft carried by and receiving the steam supply from said outlet, a casing surrounding the furnace, a blower surrounding the upper end of the furnace within the casing and substantially radially extending arms connecting the turbine, shaft and blower.

3. In combination with a furnace having a water chamber heated during operation of the furnace, an outlet for said chamber projecting through the top of the furnace, a turbine casing having a vertically directed rotor shaft carried by and receiving the steam supply from said outlet, a casing surrounding the furnace, a blower surrounding the upper end of the furnace within the casing, substantially radially extending arms connecting the turbine, shaft and blower, there being a water pan within the casing adjacent the lower end thereof, and means for directing the exhaust from the turbine into the water in said pan.

4. In a furnace having a fire chamber, a water heater disposed above the chamber for the generation of steam, a casing about the furnace overlying the water chamber, a turbine casing mounted on the water chamber and adapted to receive steam therefrom, a turbine wheel mounted within the casing for rotation about a vertical axis, and a fan comprising an annular frame structure, arms extending across the same and blades disposed about the periphery of the frame, said arms being connected with said turbine wheel for the rotation of the frame and blades thereby.

5. In a furnace having a fire chamber, a water heater disposed above the chamber for the generation of steam, a casing about the furnace overlying the water chamber, a turbine casing mounted on the water chamber and adapted to receive steam therefrom, a turbine wheel mounted within the casing for rotation about a vertical axis, and a fan comprising an annular frame structure, arms extending across the same and blades disposed about the periphery of the frame, said arms being connected with said turbine wheel for the rotation of the frame and blades thereby, said blades being disposed about the frame to extend obliquely across the peripheral portion thereof to create an upward blast of air and further being disposed between the fire chamber and the first mentioned casing.

6. In a furnace having a fire chamber, a water heater disposed above the chamber for the generation of steam, a casing about the furnace overlying the water chamber, a turbine casing mounted on the water chamber and adapted to receive steam therefrom, a turbine wheel mounted within the casing for rotation about a vertical axis, a fan comprising an annular frame structure, arms extending across the same and blades disposed about the periphery of the frame, said arms being connected with said turbine wheel for the rotation of the frame and blades thereby, a water receptacle disposed between the first mentioned casing and the fire chamber, and a steam exhaust pipe leading from the turbine casing to and terminating in the water receptacle.

In testimony whereof we hereunto affix our signatures.

JAMES H. SUMMER, JR.
LEWIS C. PINDAR.
